UNITED STATES PATENT OFFICE.

WALTER M. TAUSSIG, OF YONKERS, NEW YORK, ASSIGNOR TO THE CHAL-
LENGE CUTLERY CORPORATION, OF BRIDGEPORT, CONNECTICUT.

DESIGN FOR A HANDLE FOR RAZORS OR SIMILAR ARTICLES.

SPECIFICATION forming part of Design No. 32,382, dated March 27, 1900.

Application filed February 28, 1900. Serial No. 6,881. Term of patent 7 years.

To all whom it may concern:

Be it known that I, WALTER M. TAUSSIG, a citizen of the United States, and a resident of the city of Yonkers, in the county of Westchester, State of New York, have invented and produced a new and original Design for a Handle for Razors or Similar Articles, of which the following is a specification.

The essential feature of my design resides in the ornamentation of the handle.

In the drawings, Figure 1 is a side elevation, and Fig. 2 an edge view.

The general configuration of the handle is conventional and which comprises the two sections 1 2, both provided on its exterior with the ornamentation which is the essential feature of the design. Such ornamentation comprises the lower ground 3 and upper ground 4. The lower ground 3 has at its base the stippled surface 5, the fanciful fo-

liated figure 6, and the surmounting panel 7, inclosing an owl 8. The upper ground 4 has the surmounting stippled surface 9, bearing a geometrical figure 10 and surmounting a bunch of flowers 11, a lower foliated figure 12 and surmounting flowers 13, and a connecting-beading 14. All the ornamentation is raised.

I claim—

The design for a handle for razors and similar articles, substantially as herein shown and described.

Signed at the city of New York, in the county of New York and State of New York, this 19th day of February, 1900.

WALTER M. TAUSSIG.
